US00D974282S

(12) **United States Design Patent** (10) Patent No.: **US D974,282 S**
(45) Date of Patent: ** Jan. 3, 2023

(54) **SOLAR HOUSING MODULE**

(71) Applicant: **Solar Avances y Sistemas de Energía, S.L.**, Pedreguer (ES)

(72) Inventor: **Jaime Caselles Fornés**, Alicante (ES)

(73) Assignee: **Solar Avances y Sistemas de Energía, S.L.**, Alicante (ES)

(**) Term: **15 Years**

(21) Appl. No.: **35/511,284**

(22) Filed: **Aug. 4, 2020**

(80) **Hague Agreement Data**

Int. Filing Date: **Aug. 4, 2020**

Int. Reg. No.: **DM/209976**

Int. Reg. Date: **Aug. 4, 2020**

Int. Reg. Pub. Date: **Feb. 5, 2021**

(51) **LOC (14) Cl.** **13-04**

(52) **U.S. Cl.**

USPC **D13/102**

(58) **Field of Classification Search**

USPC D13/102, 103, 107, 108, 151, 116

CPC F24S 23/71
